GUN TYPE WELL CASING PERFORATOR

Wilfred G. Lane, Los Angeles, Calif., assignor to
The Technicraft Engineering Corp., Los Angeles, Calif., a corporation of California

Application July 16, 1935, Serial No. 31,684

6 Claims. (Cl. 81—188)

My invention relates to gun type well casing perforators and constitutes a continuation in part of my copending application for well casing perforators, Serial Number 642,410, filed November 12, 1932.

5 Among the objects of my invention are:

First, to provide in a well casing perforator a wiring arrangement which is adapted to connect a series of gun units individually with a distributor head.

10 Second, to provide a well casing perforator incorporating a wiring arrangement which extends axially along the center of the perforator gun body and around each of its gun units in such a manner that the gun units may be readily secured or removed without interfering with the wiring.

15 Third, to provide a novelly arranged contact and terminal structure adapted to withstand the explosive forces generated within the gun units as well as extreme hydrostatic pressure.

20 Fourth, to provide a wiring arrangement which incorporates a novel means of sealing the wires in place to withstand such explosive forces as may back-fire into the passages in which the wiring is disposed.

25 With these and other objects in view as may appear hereinafter, reference is made to the accompanying drawing, in which:

30 Fig. 1 is an elevational view of a gun perforator which incorporates my special wiring arrangement;

Fig. 2 is an enlarged fragmentary, longitudinal sectional view taken through 2—2 of Fig. 1;

35 Fig. 3 is a transverse sectional view through 3—3 of Fig. 2;

Fig. 4 is an enlarged fragmentary transverse sectional view taken through 4—4 of Fig. 2; and,

40 Fig. 5 is a dis-assembled view in perspective of the terminal and contact structure carried by a gun unit.

The gun perforator comprises a plurality of body sections 1 connected through an internally threaded sleeve 2 to a controller casing 3 which in turn is connected with a cable head 4 supported from a conductor core cable 5. The cable head and controller are disclosed in other pending applications.

45 Each body section 1 is in the form of a cylinder with two or more large, axially spaced, laterally extending sockets 1a, preferably facing in diametrically opposite directions. Each unit is provided with a hollow externally threaded

5 boss 1b at its upper end and a corresponding internally threaded recess 1c at its lower end whereby the body sections may be connected in axial alignment. Inasmuch as the body sections when once joined need not be separated except for infrequent replacement of a body section, the 5 contiguous ends of the body sections are beveled to form channels to facilitate welding of the body sections into a single unit, as indicated by 6.

The wall between each pair of sockets 1a and the extremities of the body sections are provided 10 with apertures 1d disposed concentrically with respect to the body sections. The several apertures 1d form with the several sockets a continuous passage from end to end of the body sections.

15 Each socket 1a is large and deep, and its back wall 1e conforms to the curvature of the body section. Intermediate its extremities and immediately forwardly of the points of intersection of the apertures 1d, each socket 1a is provided with 20 an internal annular flange or rib 1f. Outwardly of the rib, the socket is provided with coarse internal threads 1g.

25 Each socket is adapted to receive a gun unit 1 which includes a chamber block 7a adapted to pass within the flange 1f and provided with an enlarged, externally threaded outer portion 1b adapted to be screwed into the threads 1g and seat against the outer face of the rib 18. The inner end of the chamber block 7a and that portion of the corresponding socket 1a inwardly of the flange 1f together define a cup-shaped chamber A.

30 The upper body section which joins the sleeve 2 is covered at its extremity by a distributor body 35 8 formed of insulation material and carrying a plurality of contacts 8a. Said contacts are joined to a plurality of distributor wires 9, one for each contact and its gun unit.

35 Said distributor wires lead from their respective contacts through the apertures 1d. In order to clear the gun units, the lengths of distributor wires within each socket are divided, one half extending semi-circularly in each direction around and contiguous to the wall of the 45 socket 1a and inwardly of the rib 1f; that is, in the forward part of the chamber A. The wires are cemented or molded in place by means of a suitable plastic 10, such as "Plastic wood". In addition a split ring 11 of sheet insulation material is fitted within the circle formed by the wires. The plastic 10, and insulation 11 serve to protect the wires from abrasion due to repeated insertion and removal of the gun unit; also, to protect the wires from water that may enter; and 50 55

further, to protect them from damage should the gun unit "blow back".

At each socket 1a, one of the distributor wires 9 extends laterally to the back of the corresponding socket and is there secured, preferably by solder to a contact plate 13. Said contact plate is substantially oval shaped in plan and pressed to define a fraction of a sphere so as to conform to the back wall of the socket 1a. At the extremities of its longer axis, the contact plate 13 receives two screws 14 which are insulated therefrom and which screw into the gun body 1. The contact plate is backed by a conforming insulation plate 15 which is somewhat larger in area. Both the contact plate and the insulation plate are provided with apertures 13a disposed coaxially with the socket 1a.

The chamber block 7a of each gun unit is provided with a coaxially disposed cartridge receiving chamber 7c therein, the back wall of which is provided with a centered recess 1d which in turn is intersected by a small opening 7e extending to the rear end of the chamber block. The rear or outer end of the opening 7e is countersunk, as indicated by 7f.

The opening 7e and recess 1d receive a contact pin 16 comprising a small shank 16a and a relatively large head 16b. The shank 16a is insulated from the chamber block 7a by a sleeve 17 extending between the recess 1d and the countersunk end 7f. The head is insulated from the base of the recess 1d by a washer 18. The head is slightly smaller in diameter than its recess so no insulation is required around the periphery of the head. In the countersunk end 7f there is stuffed or compressed a conical sealing element or gasket 19 preferably formed of rubber. The gasket 19 is covered by a relatively large insulation disk 20. The extremity of the shank 16a protrudes beyond the disk 20 and receives a contact clip 21. Said clip is in the form of a strip of spring material tapering slightly at its ends and adapted to be bent outwardly from the disk 20 so as to yieldingly engage the contact plate 13 when the gun unit is screwed into its socket. A nut 22 retains the clip 21 in place.

The gasket 19 is particularly designed to prevent wetting of the powder in the cartridge contained by the chamber 7c should the juncture between the same or another gun unit and its socket leak and water enter the chamber A. The particular arrangement of the contact pin with its relatively massive head is designed to reduce the possibility of "blow backs" to a minimum, and pressure within the chamber forces it tightly against the base of the recess. However, it should be borne in mind that a well casing perforator is often operated under several thousand feet of liquid and that the resulting pressure within the chamber block of the gun unit is tremendous. When the hydrostatic head is excessive, and the liquid is "dead"; that is, without suspended gas particles, the gun unit may "blow back" through the contact pin with the result that damage to the distributor wires would occur were it not for the plastic 10 and insulation ring 11.

It is, of course, desirable to provide as many gun units as possible in the gun perforator. However, as the perforator is carried on a cable, and for ease in handling above ground both the weight and length is limited. This requires that the gun units be mounted as close as possible; and this, to a large extent, is made possible by the particular wiring arrangement illustrated. The only 75 waste space occurs between the body sections and

this is partly due to the fact that in boring the sockets 1a, it is more convenient to turn the shorter body section, and partly to permit salvaging of the other body sections should one become damaged beyond repair.

Though I have shown and described a particular embodiment of my invention, I do not wish to be limited thereto, but desire to include in the scope of my invention the constructions, combinations and arrangements substantially as set forth in the appended claims.

I claim:

1. In a gun type well casing perforator; a gun body including laterally directed sockets and axially disposed apertures connecting said sockets; gun units fitting said sockets, portions of said sockets being diametrically larger than said gun units to define therewith annular passages interposed between said apertures; distributor wires threaded through said apertures and said 15 passages; means for rigidly securing the lengths of said distributor wires within said annular passages; a contact element disposed at the base end of each socket, there being a terminal length of distributor wire extending from the corresponding 20 securing means and connected with said element; and a coacting contact means carried by each gun unit.

2. In a gun type well casing perforator; a gun body including laterally directed sockets and axially disposed apertures connecting said sockets; gun units fitting said sockets, there being portions of said sockets which are diametrically larger than said gun units to define therewith 30 annular passages interposed between said apertures; distributor wires threaded through said apertures and said passages; a contact element disposed at the base end of each socket, there being a distributor wire for each contact element; a coacting contact means carried by each 35 gun unit; said contact means including, an insulated contact pin extending into the gun unit, an explosive pressure resisting head for said pin positioned within the gun unit, and a yieldable contact clip carried by the outer end of said contact pin.

3. In a gun type well casing perforator; a gun body including laterally directed sockets and axially disposed apertures connecting said sockets; gun units fitting said sockets and having 50 portions spaced from the walls thereof to define therewith annular passages interposed between said apertures; distributor wires threaded through said apertures and said passages; a contact element disposed at the base end of each socket, there being a distributor wire for each contact element; a coacting contact means carried by each gun unit; said contact means including, an insulated contact pin extending into the gun unit, an explosive pressure resisting head 55 for said pin positioned within the gun unit, and a yieldable contact clip carried by the outer end of said contact pin; each gun unit having been countersunk around the protruding end of its contact pin, and a conforming sealing element forced therein.

4. In a gun unit for gun type well casing perforators; a chamber block having a cartridge receiving chamber and an aperture extending 70 from an end of the gun unit into said cartridge chamber; a contact means insulated from said chamber block and including a contact pin fitting said aperture, a contact head connected to said pin and exposed to said chamber, a sealing 75

means incorporating the side of said contact head attached to said pin and the contiguous wall of said chamber for sealing against pressures within said chamber, and a terminal carried by the outer end of said contact pin; said chamber block being countersunk at the outer end of said aperture, and a conforming sealing element forced therein.

5. A well casing perforator including a body having a lateral socket, a fixed contact within said socket adapted to be connected with a source of electric energy, a separate gun unit fitted in said socket including an inner explosive chamber, a firing pin extending through a wall of said unit from the explosive chamber and insulated from said unit, sealing means between the outer end 10 of said pin and the unit, and a yieldable contact clip carried by the outer end of said pin and engageable with the socket contact when the gun unit is fitted therein.

6. A well casing perforator including a body having a lateral socket, a fixed contact within said socket adapted to be connected with a source of electric energy, a separate gun unit fitted in said socket including an inner explosive chamber, a firing pin extending through a wall of said unit from the explosive chamber and insulated from said unit, sealing means between the outer end 10 of said pin and the unit, and a yieldable contact clip carried by the outer end of said pin and engageable with the socket contact when the gun unit is fitted therein.
